CLAIM

I claim, the ornamental design for a lock body, as shown and described.

DESCRIPTION

FIG. 1 is a perspective view of a lock body showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view thereof, with the article shown in its environmental use;

FIG. 9 is another perspective view thereof, with the article shown in its environmental use; and,

FIG. 10 is another perspective view thereof, with the article shown in its environmental use.

The broken lines showing the environment is for illustrative purpose only and forms no part of the claimed design.
